CLAIM

The ornamental design for a slotted safety closure having oversized thumbpads, as shown and described.

DESCRIPTION

FIG. 1 is a top perspective view of a slotted safety closure having oversized thumbpads according to a preferred embodiment of the present invention;

FIG. 2 is a front view of the slotted safety closure having oversized thumbpads according to FIG. 1;

FIG. 3 is a left-side view of the slotted safety closure having oversized thumbpads according to FIG. 1;

FIG. 4 is a top view of the slotted safety closure having oversized thumbpads according to FIG. 1;

FIG. 5 is a bottom view of the slotted safety closure having oversized thumbpads according to FIG. 1; and,

FIG. 6 is a bottom perspective view of the slotted safety closure having oversized thumbpads according to FIG. 1.
